R. D. LITWILLER

THRASHING MACHINE CYLINDER WRENCH

Filed Sept. 30, 1924

Patented Mar. 30, 1926.

UNITED STATES PATENT OFFICE.

REUBEN D. LITWILLER, OF SEWARD, NEBRASKA.

THRASHING-MACHINE-CYLINDER WRENCH.

Application filed September 30, 1924. Serial No. 740,840.

To all whom it may concern:

Be it known that I, REUBEN D. LITWILLER, a citizen of the United States, residing at Seward, in the county of Seward and State of Nebraska, have invented certain new and useful Improvements in Thrashing-Machine-Cylinder Wrenches, of which the following is a specification.

My invention relates to wrenches which are designed for loosening and tightening the nuts which are inaccessible to wrenches of the usual types. Since my wrench was designed initially for use on the nuts which hold the teeth in place in thrashing machine cylinders, and since such nuts are probably the most inaccessible of any in common use, I will describe my invention as it relates to this particular use.

Referring now to my drawings, in which like reference characters refer to like parts in the description.

Figure 1 is a side view of my wrench as seen when in engagement with one of the nuts of a thrashing machine cylinder.

Figure 2 is a view on line 2—2 of Figure 1, looking in the direction of the arrow.

Figure 3 is a view in perspective of the operative parts of the wrench.

Figure 4 is a sectional view on line 4—4 of Figure 2 looking in the direction of the arrow, a fragment of the thrashing machine being shown but a portion of the handle of the wrench being omitted.

Figure 5 shows an alternative method of assembling the wrench.

My wrench consists of four parts only: an actuating or handle member 10, a nut engaging member 20, a support 30 and a sprocket chain 40 or other similar device for imparting the movement of the handle member to the nut engaging member, I will describe these elements in detail.

The handle member 10 is preferably formed out of a rod of suitable material such as steel shafting. It has a slightly reduced operative end 11, the shoulder being shown at 12. On the reduced end 11 is a sprocket wheel 13 which in effect is integral with the handle member 10. While this sprocket wheel may be keyed or otherwise secured to the handle member, I prefer either to place the block of steel in a lathe and to thus form the entire handle member with its sprocket wheel 13 or to shrink an annular steel disc on the reduced end 11 and then to cut the teeth in the disc on the lathe. By these methods I

obtain absolute symmetry of the teeth about their axis. The sprocket wheel must be secured to the handle member in order to be rotated thereby and it must be mechanically true with respect to its axis in order to avoid binding. These results can best be obtained on the lathe by either of the methods which I have described. At its opposite end the handle member is provided with an eye 14 for slidably receiving the handle proper 15, this handle being manipulated in the manner usual in close places.

The nut engaging member 20 includes a nut engaging portion 21 and a shaft portion 22, the shaft portion having a sprocket wheel 23 formed thereon in the manner described in connection with the sprocket wheel 13. The nut engaging portion 21 may be of any desired form or size. In fact it is my purpose to construct the nut engaging element 20 in forms and sizes to fit nuts of all sizes and types commonly used in thrashing machines and similar places so that the purchaser of the wrench may either select the particular one which he needs or stock up with an assortment of nut engaging elements to meet all of his various needs. The shaft portion 22 is preferably tubular, the reason for this being that bolts sometimes protrude beyond their nuts. In such cases the tubular cavity is adapted to receive the protruding end of the bolt as shown in Figure 4.

The support 30 is preferably in the form of a single casting and it comprises two plates 31, 31 and a spacer 32. The plates 31 are identical in form and they are provided with aligning semicylindrical bearing surfaces for receiving the shaft portions of the handle member 10 and the nut engaging member 20. The spacer 32 holds the plates 31 parallel to each other and spaced from each other a sufficient distance to allow clearance for the sprocket chain 40. The spacer has its ends so positioned as to afford ample clearance for the sprocket wheels 13 and 23 as shown in Figure 4.

In assembling the wrench, the handle portion 10 and the nut engaging portion 20 are placed in their respective bearing sockets in the spacing member 30 as shown in Figure 3 and the sprocket chain is then secured to the sprocket wheels 13 and 23. The sprocket chain is provided with the usual separable link whereby it may be easily placed in position or removed therefrom. When in place the sprocket chain has two functions.

It of course imparts the movement of the handle to the nut engaging element, and it secures the various parts in their assembled relation.

5 In some cases it is desirable to position the nut engaging element 20 on the side opposite the handle 10. This may easily be done by assembling the parts as shown in Figure 5, which is the reverse of the position shown
10 in Figures 1, 3, and 4. When thus assembled the wrench may be used for loosening or tightening the nuts on the connecting rods of Ford automobiles or other similar but inaccessible nuts. The wrench, having
15 no ratchet in its actuating mechanism, can be as readily employed for either tightening or loosening the nuts.

As before stated, my wrench was initially and primarily designed for use on the nuts
20 of a thrashing machine cylinder, other uses being secondary and incidental. In Figures 1 and 4, I show a fragment of a thrashing machine cylinder and the position of the wrench when functioning to loosen or tighten one of the nuts. In these figures A indicates one of the end rings of the cylinder. The teeth are shown at B and the ends of the longitudinal bars of the separator are shown at C. The nuts which secure the
25 teeth to the cylinder are inaccessible to wrenches of the ordinary types but they are easily reached with my wrench.

The great advantage of my wrench resides in the small number of its parts and the extreme simplicity of its construction. Both bearings are semicircular and the shafts are held in the bearings by the chain. When the detachable link is removed the entire wrench becomes disassembled. In prior
30 wrenches it has been necessary to assemble them by the use of tools or machines, since

the sprocket wheels or other gears must have a definite and fixed position relative to the closed bearings which could be obtained only by the use of special tools. The advantage of this resides in the ease and facility with which the wrench can be altered to fit nuts of various types and sizes. The parts of all wrenches are subject to unequal wear and in most cases the wrench must 45 either be discarded or sent to the machine shop for repair. With my wrench the device can be disassembled and then assembled with the replacement part in a few minutes' time and without any tools whatever. 50

Having thus described my invention in terms which will be readily understood by others skilled in the art to which it pertains, what I claim as new and desire to secure by Letters Patent of the United States is:— 60

A thrashing machine cylinder wrench comprising a supporting block, a handle member, a socket member, and a sprocket chain, said supporting block including two spaced plates having arcuate bearings in 65 their extremities open at one side, said handle member and said socket member each having their sole bearings in the arcuate bearings of said supporting block, said handle member and said socket member 70 each having a single circle of sprocket teeth projecting radially therefrom and integral therewith, and said sprocket chain having a single row of links and passing between said plates and over the sprocket teeth of 75 both said handle member and said socket member, the arrangement being such that the wrench may be entirely disassembled by removing said sprocket chain.

In testimony whereof I affix my signature.

REUBEN D. LITWILLER.
